UNITED STATES PATENT OFFICE.

FREDERICK S. OREM, OF BALTIMORE, MARYLAND.

CARBURETER.

1,254,723.

Specification of Letters Patent. Patented Jan. 29, 1918.

Application filed February 3, 1916. Serial No. 77,094.

To all whom it may concern:

Be it known that I, FREDERICK STRATTNER OREM, a citizen of the United States, residing at Baltimore, Maryland, have invented 5 certain new and useful Improvements in Carbureters, of which the following is a specification.

The objects of this invention are first:—to produce a carbureter that will entirely fulfil 10 the requirements of an internal combustion engine, will be simple in construction and operation and will require no adjustments after its initial application to the engine. Second: to provide a construction which will 15 furnish the proper proportion of gasolene and air at all speeds of the motor and this regardless of temperature, *i. e.* cold or warm weather, without any adjustments, whereby with such proper proportions of gasolene 20 and air, which constitutes an ideal explosive mixture, there will be complete combustion, which will mean more power, less consumption of gasolene, and no deposit of carbon from this source.

25 In my improved carbureter the gasolene flows to the motor by gravity through ports of sufficient size and number and this gasolene supply is independent of the suction of the motor and the velocity of the air passing 30 through the carbureter.

Further, the air can be of sufficient amount 35 independent of the gasolene supply to the motor, both the gasolene and air supply being under direct control of the operator, and when the gasolene and air mixture produced by this carbureter is ignited, a blue flame 40 will result. For quick accelerating, when the throttle lever is thrown in wide open position by the operator, the maximum 45 amount of gasolene and air is permitted to enter the motor at once. The complete control of gasolene and air supply are under the control of the operator and do not depend upon the vacuum and velocity of air to regulate 50 the flow of gasolene as employed in carbureters now in use.

My invention includes the novel features 55 of construction and arrangement and combination of parts hereinafter described and particularly defined by the appended claims, an embodiment of the invention being illus-

trated in the accompanying drawings, in which—

Figure 1 is a sectional view of a carbureter.

Fig. 2 is a detail view of the throttle lever. 55

Fig. 3 is a plan view of the piston and valve stem.

Fig. 4 is a plan of the guide for the valve stem.

Referring by reference characters to this 60 drawing, A, in Fig. 1, is the opening through which the mixture passes to the motor, the flange 1 being designed to be bolted to a similar flange on the intake manifold of motor (not shown). B designates the opening 65 through which warm air passes to the carbureter. C designates a half union attachment for connection to a pipe, (not shown) leading to any suitable gasolene supply tank, which should be at the proper distance or 70 height above carbureter to insure the proper flow of gasolene to the carbureter at all times. 2 designates a valve of ring form which has suitably secured to its upper surface a flexible diaphragm 3. 4 designates a 75 bolt which is fitted or screwed into the valve stem 5 and clamps the diaphragm tightly to the end of the valve stem 5. The valve stem 5 has integral with, or connected to it, through arms F, F', F'', cylinder piston or 80 sliding sleeve 6 which is fitted with rings d, d' and also grooves e, e', and which works within cylindrical member 13.

This member is preferably formed separately of and seated within the body of the 85 carbureter, and at its upper edge is provided with a valve seat 13^a for the valve 2. On the lower end of valve stem 5 is carried a valve 7, beneath which is a valve or guiding stem 9 passing through guide 8. A helical 90 spring 10 encircling this stem 9 between guide 8 and lock nuts 11, tends to draw said stem 9 normally downward.

The function of the diaphragm 3 is to provide a slight amount of play or relative 95 movement between valves 2 and 7.

12 designates a cap, in the center of which is a guide for a prolongation 9^a of stem 9. The cylinder 13 is provided with a number of small openings or nozzles 15 arranged at 100 different elevations (preferably helically), which allow gasolene to flow from annular

chamber D to chamber H, when uncovered by piston valve 6.

16 is a fork shaped guide for a lever 17 which, by its engagement with the base of 5 the fork tends to hold the needle valve seated. The lower end of guide 16 is threaded to be engaged by a nut 18, and a flexible diaphragm 19 is held tightly between guide member 16 and nut 18. This flexible 10 diaphragm 19 is also held on its periphery by a clamping ring 20, which has a threaded exterior engaging internal threads on a portion of the wall of chamber G and clamps the diaphragm against shoulder g' . Nut 15 18 is provided with a cylindrical guide 18^a at its lower end for the upper part of helical spring 21, the lower part of which rests in a similar guide carried by valve stem 22, which has a needle valve on its lower end, 20 which engages with seat 23, which, when closed, prevents communication from chamber E to chamber E'. The lever 17 is pivotally supported from the wall of the casing by link 24. Chamber G is always in 25 communication with chamber A through opening α in casing 14, which opening permits lever 17 to move vertically. Chambers E and G are made tight by cap nuts 30 and 31.

30. 25 designates a bell crank lever which is attached to shaft 26, which passes through casing 14 and is journaled in the walls thereof. Shaft 26 has an arm 27 which engages at its end with a slot in bolt 4. A helical 35 spring 25^a is attached to crank 25 near its upper end and to a convenient part of frame of car, which pulls in opposite direction to arrow. A bolt or set screw 28, passing through a lug 29 on casing 14, and bearing 40 against projection 25^b of lever 25, serves as an adjustable stop for limiting the movement of lever 25.

The operation of my above described carbureter is as follows:—

45 The suction of motor created by the pistons of the same causes valve 2 and flexible diaphragm 3, together with valve stem 5 and piston valve 6 and valve 7 and stem 9 to be drawn upward, unseating valves 2 and 50 7 from their respective seats. There is a flange on valve 2, marked 2^a, the object of which is to prevent it from opening until one or more of ports 15 are open. The upward movement, above referred to, opens 55 the lowermost ports 15, which ports or nozzles allow gasoline to flow by gravity from annular chamber D to chamber H. At the same time lever 17 is raised also off the bottom of forked guide 16, which allows the 60 flexible diaphragm 19 to move upward, which removes the pressure on the helical spring 21. This permits the needle valve 22 to leave its seat 23, which allows gasoline to flow from tank, not shown, through

chambers E and E' to annular chamber D 65 and through ports 15, which are opened by the movement of piston valve 6 upward. Here the gasoline meets and mixes with the air which is drawn upward around the edge of the valve 7 in a thin annular stream. 70

The amount of opening of valves 2 and 7 and travel of piston 6 is regulated by the lock bolt 28 and the slot in bolt 4, the clearance between the bottom of slot in nut 4 and bottom of arm 27 being regulated by bolt 28. 75
Turning bolt to right increases the lift and to left decreases the lift of valves 2 and 7 and travel of piston valve 6.

When the pressure of lever 17, which is held in closed position by spring 10, is removed by the suction of motor raising valves 2 and 7 and piston valve 6, the suction of motor, through the space provided in casing 14 for lever 17 to rise, is exerted on the upper surface of flexible diaphragm 19, which causes the flexible diaphragm to rise, removing the tension or pressure on spring 21 and allowing valve 22 to become unseated, which permits gasoline to flow by gravity from tank to chamber E'. The amount of opening of the valves 2 and 7 due to flange 2^a on valve 2 and travel of piston 6 under the suction is sufficient to start motor, the amount of play or lost motion of arm 27 in the slot of member 4 being sufficient for this purpose. By that I mean when adjusted by bolt 28, the valves 2 and 7 and piston valve 6 are operated automatically through the suction of the motor and at the same time the needle valve is allowed to open automatically by taking the pressure off the flexible diaphragm 19 and the suction of motor draws the diaphragm away from spring 21 and gasoline fills chamber E', as already stated. To speed the motor, it is only necessary to open valves 2 and 7 and lift piston valve 6 through crank 25 in the direction of arrow, Fig. 2. The jaw of crank 25 is provided with the usual foot and hand throttle apparatus, as already installed in cars.

The speed of the motor is controlled entirely by the operator through the opening or closing movement of valves 2 and 7, which admits a greater or less amount of air through opening B, and the raising and lowering of piston valve 6, which opens more or less of the nozzles or ports sufficient in number and size to give the correct mixture and this regardless of speed of motor. 115 120

After the maximum amount of gasolene is allowed to pass through the nozzles or ports 15 by raising piston 6 through crank 25, the valves 2 and 7 are opened further, which, however, only admits warmed air (no more nozzles being opened) and herein lies the economical side of the carburetor, as it can be readily seen that when the requisite

amount of gasoline for the motor is supplied through the nozzles, one can, by further opening valves 2 and 7, add warm air after this, which will make the explosive mixture 5 more powerful and at the same time when more oxygen is added, it will burn any deposit of carbon resulting from lubricating oil. It can further be seen that the operation of this carburetor does not depend on a 10 vacuum to draw the gasoline out of jet or jets, as in carburetors now in use.

It will not make any difference how cold gasoline might be, it will flow by gravity to chamber II when nozzles or ports 15 are un- 15 covered by piston valve 6.

For starting in very cold weather, while it would probably not be necessary, one could, however, open the valves 2 and 7 and raise piston valve 6 through lever 25 for a 20 moment, which would allow gasoline to flow from nozzles or ports 15 to chamber II, which would cause a very rich mixture.

It is obvious that if, after the motor is started, the operator were to open valves 2 25 and 7 and lift piston valve 6 to its full extent, the maximum amount of gasoline and air would be permitted to enter motor through chambers II and A, which would cause motor to attain its maximum number of revolutions at once.

Should the valves 2 and 7 and piston valve 6 be left in open position inadvertently through connections under control of operator, either by hand or foot manipulations, 35 the vacuum ceasing when motor stops would allow flexible diaphragm 19 to resume a position that would close needle valve 22, thereby preventing the gasoline from passing to chamber E' from the supply tank. 40 When the valve 22 is closed no gasoline can escape from chamber E' when the engine is at rest, due to the smallness of the jet orifices and their upward inclination, coupled with the fact that there is no way for air to 45 get into chamber E', except through orifices 15, the upper part of chamber E' being closed by diaphragm 19. It is intended that the tension of spring 10 should be such as to seat valve 2 first and through the flexible diaphragm 3 and valve stem 5 seat 50 valve 7.

Piston 6 is provided with neat fitting rings intended to prevent the passage of gasoline from annular chamber D to chamber II 55 through ports 15 when motor is at rest.

It also provide grooves, e, e', to reduce friction and also serve the purpose of holding any condensation from passing from annular chamber D to chamber II through ports 60 or nozzles 15 when motor is at rest. Valves 2 and 7 will also prevent any leaking of gasoline into chamber A or air inlet B when motor is at rest.

With this carburetor it is impossible for

a car to take fire from back firing of motor. 65 Back firing is due to the premature explosion of a charge which causes flame to be driven back through carburetor, thereby igniting any gasoline that might be in intake manifold and carburetor. With my carburetor it is impossible for any flame to enter carburetor, as valve 2 would be seated instantly, preventing escape of flame to interior of carburetor.

The gasoline tank (not shown) should 75 be located at the proper height above carburetor. After the engine is started air and gasoline supply is controlled mechanically and not automatically as now employed in carburetors.

Having thus described my invention, what I claim is:—

1. A carburetor having a chamber with a plurality of gasoline ports leading through the wall thereof, a piston valve working in 85 said chamber and covering and uncovering said ports, means for supplying gasoline by gravity through said ports when uncovered, and an air supply valve connected to move in unison with said piston valve.

2. A carburetor having a cylindrical chamber adapted for connection at its upper end with the engine intake and having a plurality of gasoline ports leading through the wall at different heights, an annular piston valve working in said chamber, means for feeding gasoline by gravity through said ports when uncovered by the piston valve, an air supply passage connected to the bottom of said chamber and a valve closing said air supply passage and connected to move in unison with said piston valve.

3. A carburetor having a carbureting chamber with a plurality of ports in the walls thereof at different elevations, a hollow piston valve working in said chamber, means for feeding gasoline through said ports by gravity when the ports are uncovered, an air supply passage to the bottom of said chamber, a valve controlling the passage of air to the chamber, a valve above the piston valve controlling the passage of the mixture from said chamber and means connecting said three valves for causing them to operate in unison.

4. A carburetor comprising a cylindrical carbureting chamber having gasoline ports through the wall thereof at different elevations, a cylindrical piston valve in said chamber uncovering said ports, a valve for controlling the admission of air to the bottom of said carbureting chamber, a valve for controlling the passage of the mixture from said chamber, said three valves being connected to operate in unison and an operating 125 arm having a lost motion connection with said valves.

5. A carburetor having a carbureting

chamber with a plurality of gasoline ports leading through the wall thereof, means for supplying gasoline by gravity through said ports, a piston valve in said chamber controlling said ports, a valve controlling the admission of air to the bottom of said carbureting chamber, a second valve controlling the passage of the mixture from said chamber, said three valves being connected to move in unison, a cut-off for the gasoline feed when the engine is at rest, and means permitting opening of said cut-off when said three valves are operated.

6. A carbureter comprising a carbureting chamber having a plurality of gasoline ports, means for feeding gasoline through the same by gravity, upper and lower valves controlling the entrance of air to and its exit from said carbureting chamber, a central stem connecting said valves and also connected to said piston valve, a gasoline cut-off valve, means connecting said stem with said cut-off, whereby the latter is allowed to open on the upward movement of the stem, and an operating lever connected with said stem.

7. A carbureter having an annular chamber adapted for connection at its upper end with the engine intake and having a plurality of gasoline ports leading through the wall, a cylindrical piston valve working in said chamber and controlling said ports, a chamber for supplying gasoline to said ports, an air supply passage connected to the bottom of said chamber and a valve closing said air supply passage and connected to move in unison with said piston valve, means for feeding gasoline to said chamber, a valve controlling said feed, and means for closing said valve when said first named valves are closed.

8. A carbureter having a carbureting

chamber with a plurality of gasoline ports, a hollow piston valve in said chamber controlling said ports, a valve controlling the admission of air to the bottom of said carbureting chamber, a second valve controlling the passage of the mixture from said chamber, said three valves being connected to move in unison, a gasoline chamber connected with said ports and also with said source of supply, a valve controlling said supply, a diaphragm above said chamber, a spring between said diaphragm and valve, a chamber above said diaphragm communicating with the space above the carbureting chamber, and means whereby the closing of said connected valves places pressure on the diaphragm.

9. A carbureter having a carbureting chamber with a plurality of gasoline ports, a hollow piston valve in said chamber controlling said ports, a valve controlling the admission of air to the bottom of said carbureting chamber, a second valve controlling the passage of the mixture from said chamber, said three valves being connected to move in unison, a spring tending normally to close said valves, a gasoline chamber connected with said ports and also with said source of supply, a valve controlling said supply, a diaphragm above said chamber, a spring between said diaphragm and valve, a chamber above said diaphragm communicating with the space above the carbureting chamber, and means whereby the closing of said connected valves places pressure on the diaphragm.

In testimony whereof I affix my signature in the presence of two witnesses.

FREDERICK S. OREM.
